US0D1005141S

(12) **United States Design Patent** (10) Patent No.: **US D1,005,141 S**
(45) Date of Patent: ** *Nov. 21, 2023

(54) **TRACKING DEVICE**

(71) Applicant: **Tile, Inc.**, San Mateo, CA (US)

(72) Inventors: **Muhammad Umair**, Pleasanton, CA (US); **Winnie Wong**, Castro Valley, CA (US)

(73) Assignee: **Tile, Inc.**, San Mateo, CA (US)

(*) Notice: This patent is subject to a terminal disclaimer.

(**) Term: **15 Years**

(21) Appl. No.: **29/857,500**

(22) Filed: **Oct. 21, 2022**

Related U.S. Application Data

(62) Division of application No. 29/772,464, filed on Mar. 2, 2021, now Pat. No. Des. 969,634.

(57) **CLAIM**

The ornamental design for a tracking device, as shown and described.

DESCRIPTION

FIG. 1 is a top, front, and right side perspective view of a tracking device;

FIG. 2 is a bottom, front, and right side perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings showing portions of the tracking device are included for the purpose of illustrating environmental structure and form no part of the claimed design.

1 Claim, 8 Drawing Sheets
